UNITED STATES PATENT OFFICE.

JOHN H. SHAW, OF CHICAGO, ILLINOIS.

BOOK-BINDER'S PRESS-BOARD.

SPECIFICATION forming part of Letters Patent No. 399,573, dated March 12, 1889.

Application filed December 11, 1888. Serial No. 293,148. (No model.)

To all whom it may concern:

Be it known that I, JOHN H. SHAW, a citizen of the United States, residing at Chicago, in the county of Cook and State of Illinois, have 5 invented a new and useful Improvement in Book-Binders' Press-Boards, of which the following is a specification.

My said invention will be fully described hereinafter with reference to the accompanying drawings, in which—

Figure 1 represents a plan of a press-board embracing my improvement in its construction, and Fig. 2 a transverse vertical section of the same so made as to display one of the 15 spring-rods B.

Such press-boards have usually been made of cherry-wood, because that kind of wood is hard and is capable of a high degree of polish. Any other suitable material, however, may be 20 used.

The press-board itself is preferably made up of several narrow boards, *a*, the joining edges of which are cemented together by means of glue or other suitable cement, so as 25 to form practically a single board of a smooth, even, and level surface. Such boards have been sometimes made with strips of board inserted into grooves cut into each end of the board, with the design of preventing spring- 30 ing or warping and of holding the ends of all the narrow parts *a* in the same plane; but even with the use of such end strips such boards have been found much liable to split and warp under the heavy pressure brought 35 to bear upon them in book-binding, especially when the bed upon which the book-paper is placed to undergo pressure yields or is

uneven, the press-board being on top of the pile of leaves of paper. Now, in order to avoid these defects in such boards as have heretofore been in use, and to render them elastic and durable, I bore round holes of suitable caliber into one side edge of the board *A*, nearly through its entire breadth, one hole near each end, and insert into them round 45 steel rods *B*, of sufficient size to fill them, as shown in Fig. 2. The rods need not be quite as long as the holes, which at the entering ends may be plugged up to make a neat finish. The steel rods will effectually prevent the 50 board from cracking and breaking lengthwise by reason of any sharp elevations or depressions in the bed under the pile of paper. Under great pressure, in case of such unevenness existing, the board will yield sufficiently, but 55 not break, and by reason of the action of the spring-rods it will resume its proper level as soon as it is allowed to do so without being injured, and it will last in perfect condition 60 for a long time though in constant use.

What I claim as my invention, and desire to secure by Letters Patent, is—

As a new article of manufacture, a book-binder's press-board, *A*, provided with the steel spring-rods *B*, adapting said board to 65 yield in a limited degree to unequal pressures without breaking, and to resume its proper and original form when relieved, substantially as described.

JOHN H. SHAW.
